UNITED STATES PATENT OFFICE.

FREDERICK GEOFFREY LEES JOHNSON, OF WESTMINSTER, LONDON, ENGLAND, AS
SIGNOR TO VICKERS LIMITED, OF WESTMINSTER, ENGLAND.

TIME FUSE FOR PROJECTILES.

Application filed July 19, 1927, Serial No. 206,828, and in Great Britain June 17, 1926.

This invention relates to projectile time fuses of the kind having a chamber or dome into which pass the gases resulting from the burning of the time ring or fuse composition 5 and from which the gases pass to the atmosphere through one or more small holes. The chief object of the present invention is to provide an improved construction of fuse of this character such that a constant pressure 10 is maintained within the said chamber at all altitudes during the flight of the projectile so that the fuse composition will be burning under constant conditions as regards pressure and will therefore not give 15 the undesired variations in burning time which are inherent in fuses heretofore constructed or proposed.

According to the present invention the escape of the gases from the chamber to the atmosphere or on their way to the atmosphere takes place through a suitably shaped nozzle the outer end of which is subjected to a suction effect during the flight of the projectile such that a certain ratio between the 25 pressure at the outer end of the nozzle and the inner end of the nozzle (i. e. the interior of the chamber) is produced, this ratio being below that which is known to give the maximum velocity of flow through the nozzle, and the size of the nozzle is so chosen 30 that at this maximum velocity the gases generated (or as much of the gases as is not condensed in the chamber) will escape as fast as they are generated so that the pressure in the chamber will remain substantially atmospheric. In the preferred constructional form of the invention the aforesaid chamber is constituted by a cap mounted in front of the adjustable time ring and the nozzle is arranged at the front end of 35 this cap co-axially with respect to the axis of the shell so as to avoid disturbances due to the rotation of the shell.

In order that the said invention may be 40 clearly understood and readily carried into effect the same will now be described more fully with reference to the accompanying drawings, in which:—

Figure 1 is an axial section shewing a 45 fuse constructed according to the invention, the time ring being set to the safety position.

Figure 2 is a section taken approximately 50 on the line 2, 2 of Figure 1.

Figure 3 is an underneath plan of the

time ring shewing the fuse composition therein,

Figure 4 is a sectional elevation viewed from the left of Figure 1,

Figure 5 is a section taken approximately 60 on the line 5, 5 of Figure 2,

Figure 6 is a section taken approximately 65 on the line 6, 6 of Figure 2,

Figure 7 is an enlarged view of the nozzle, and

Figure 8 is a view similar to Figure 1 shewing the fuse with a percussion ignition device added.

A is the fuse body carrying the usual magazine A¹ and powder pellets A², A² leading 70 to the latter, B is the adjustable time ring rotatably mounted upon a forwardly extending and axial stem A³ of the fuse body A and held in place by a nut B¹ and a spring B², C is the cap forming the aforesaid chamber, this cap carrying a plug D formed with the nozzle D¹ and also carrying a screw-threaded nose E which holds the plug in position and the further purpose 75 of which will be explained later.

In the example shewn the time ring B carries the time ignition pellet b which, on shock of discharge, sets back to bring the detonator cap b¹ against the needle b² as is well understood. When the time ring is 80 set to any but the safety position the flash from the cap b¹ passes through a hole b³ and ignites the end b⁴ of the fuse composition carried by a channel in the ring B, this composition burning towards the other 85 end b⁵ until the pellets A², A² leading to the magazine A¹ are ignited. As the ignition device b, b¹, b² is carried by the time ring B the fuse composition is always 90 ignited at the end b⁴ so that there is only one surface burning at one time and in consequence there is a practically constant rate 95 of evolution of gas from the burning composition which is important for the successful functioning of the invention.

Close to the end b⁴ of the fuse composition the ring B has a hole b⁶ leading into the interior of the cap C so that the gas as it is evolved from the fuse composition 100 enters the said interior and passes to the atmosphere through the nozzle D¹ in the plug D, through a central recess E¹ in the nose E and through holes e, e—in this nose. The said holes are rearwardly directed as 105 shewn and terminate at their outer ends in

an annular recess E^2 in the nose E , leaving a flange E^3 between which and the front part of the cap C a space e^x exists as shewn. This arrangement causes a suction effect 5 to be produced upon the holes e, e and therefore upon the outer end of the nozzle D^1 , during the passage of the projectile through the air. The said nozzle preferably has a divergent cone of an angle of from about 10 2.5° to 4.5° which has been found to give a maximum rate of flow, in the case of air, when the ratio of pressure between its inner and outer ends is at or less than 0.8 and in the case of carbon-di-oxide (the index of 15 adiabatic expansion of which is 1.28 compared with 1.4 for air) when the said ratio of pressure is at or less than 0.85. Consequently under these conditions it becomes necessary to produce a suction by means of 20 the nose E due to the forward velocity of the projectile such as will give an absolute pressure at the outer end of the nozzle substantially less than the critical pressure (about 12.7 lbs. per square inch absolute) 25 which suction is produced by suitably dimensioning the parts e, E^2, E^3 and e^x in accordance with principles which are well understood. The said absolute pressure may be about 11 lbs. per square inch. As the 30 pressure of the atmosphere decreases at high altitudes the aforesaid absolute pressure decreases correspondingly and the aforesaid ratio of pressure remains substantially less than the critical ratio hereinbefore defined. 35 The diameter of the throat of the nozzle necessary to enable the gases to escape as fast as they are generated will vary with different types of powders but with the standard No. 80 fuse composition of black powder, the 40 composition channel having a cross-sectional area of .022 square inch and a full burning time (when the projectile is at rest) of about 22 seconds, a diameter of .02975 inch would be sufficient, with a 45 chamber of a capacity of about 8 cubic inches, to prevent rise of pressure in the chamber. Under these circumstances the rate of burning of the fuse composition will be constant whatever altitude the shell may reach. The length of the nozzle is preferably .375 inch and it has a flared entry at its inner end of about .1 inch radius; the 50 diverging cone angle is between 2.5° and 4.5° as aforesaid. In view of space limitations in small calibre shell a reduction in the gas chamber capacity is desirable, and if a fuse composition be used in which the non-gaseous products of combustion are reduced to a minimum the gas chamber may be made 55 substantially smaller, viz, about 2 to 3 cubic ins. which could be the case in the construction illustrated. The larger capacity of 8 cubic inches previously mentioned is necessary 60 when black powder composition is used, to allow the nozzle to be placed in a posi-

tion where the possibility of fouling from the non-gaseous products of combustion (which, with black powder as used in the standard No. 80 fuse, average over fifty per cent of the total) is unlikely to occur. In 70 any case the interior of the chamber is preferably made of the shape shown so that the non-gaseous products of combustion will be centrifugally separated by the spin of the projectile and will settle in the largest 75 diameter portion of the chamber.

The construction shewn by Figure 8 is substantially the same as that above described except that a percussion device is incorporated in the rear part of the fuse 80 body, this device comprising a pellet F , a detonator cap F^1 carried by this pellet and a needle F^2 on which the cap F^1 impinges when the projectile strikes an obstacle.

Although we have shewn only one nozzle 85 D^1 more than one can be employed in which case the sum of the cross-sectional areas of the throats of the nozzles should be approximately equal to the cross-sectional throat 90 area required for a single nozzle.

What I claim and desire to secure by Letters Patent of the United States is:—

1. In a projectile time fuse, the combination with a chamber into which pass the gases resulting from the burning of the fuse 95 composition and an outlet device through which said gases pass from said chamber to the atmosphere, of means for subjecting said device to a suction effect during the flight 100 of the projectile so as to produce a ratio between the pressures at the outer end of the device and the inner end of the device (i. e. the interior of said chamber) below that which gives the maximum velocity of flow 105 through said device, the cross-sectional size 110 of the outlet in said device being such that at this maximum velocity the gases will escape as fast as they are generated so that the pressure within the chamber will remain substantially atmospheric.

2. In a projectile time fuse, the combination with a chamber into which pass the gases resulting from the burning of the fuse 115 composition, of a nozzle through which said gases pass from said chamber to the atmosphere, means for subjecting said nozzle to a suction effect during the flight of the projectile so as to produce a ratio between the pressure at the outer end of the nozzle and the inner end of the nozzle (i. e. the interior 120 of said chamber) below that which gives the maximum velocity of flow through said nozzle, the cross-sectional area of the throat of said nozzle being such that at this maximum velocity the gases will escape as fast as they are generated so that the pressure within the chamber will remain substantially 125 atmospheric.

3. In a projectile time fuse, the combination of a hollow cap mounted in front of the 130

adjustable time ring of the fuse, a nozzle arranged at the front end of said cap coaxially with respect to the axis of the projectile, and means for subjecting said nozzle 5 to a suction effect during the flight of the projectile so as to produce a ratio between the pressures at the outer end of the nozzle and the inner end of the nozzle (i. e. the interior of said cap) below that which gives 10 the maximum velocity of flow through said nozzle, the cross-sectional area of the throat of said nozzle being such that at this maximum velocity the gases will escape as fast as they are generated so that the pressure 15 within the cap will remain substantially atmospheric.

4. In a projectile time fuse, the combination of a hollow cap mounted in front of the adjustable time ring of the fuse, a nozzle arranged at the front end of said cap coaxially with respect to the axis of the projectile, a nose on the front of said cap for subjecting said nozzle to a suction effect during the flight of the projectile so as to produce a ratio between the pressures at the outer end of the nozzle and the inner end of the nozzle (i. e. the interior of said cap) below that which gives the maximum velocity of flow through said nozzle, the cross- 20 sectional area of the throat of said nozzle being such that at this maximum velocity

the gases will escape as fast as they are generated so that the pressure within the cap will remain substantially atmospheric.

5. In a projectile time fuse, the combination with the elements claimed in claim 1 and the adjustable element bearing the fuse composition, of an ignition device carried by said adjustable element for igniting said fuse composition at one end thereof at any 35 setting of said adjustable element.

6. In a projectile time fuse, the combination with the elements claimed in claim 2 and the adjustable element bearing the fuse composition, of an ignition device carried by said adjustable element for igniting said 40 fuse composition at one end thereof at any setting of said adjustable element.

7. In a projectile time fuse, the combination with the elements claimed in claim 3, 45 of an ignition device carried by the adjustable time ring for igniting the fuse composition carried thereby at one end thereof at any setting of said ring.

8. In a projectile time fuse, the combination with the elements claimed in claim 4, 50 of an ignition device carried by the adjustable time ring for igniting the fuse composition carried thereby at one end thereof at any setting of said ring.

FREDERICK GEOFFREY LEES JOHNSON.
